(57) **CLAIM**

The ornamental design for a cup with lid and straw, as shown and described.

DESCRIPTION

FIG. 1 is a front, top perspective view of a cup with lid and straw, showing my new design;

FIG. 2 is a rear, bottom perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is an exploded front, top perspective view of the cup with lid and straw; and,

FIG. 9 is an exploded front elevational view of the cup with lid and straw.

The dashed broken lines in the figures are for the purposes of illustrating portions of the cup with lid and straw, which form no part of the claimed design.

1 Claim, 9 Drawing Sheets
